UNITED STATES PATENT OFFICE.

ERNEST SEGEL, OF CHICAGO, ILLINOIS.

SUSPENDERS.

1,359,754.

Specification of Letters Patent. Patented Nov. 23, 1920.

Application filed December 8, 1919. Serial No. 343,257.

To all whom it may concern:

Be it known that I, ERNEST SEGEL, a citizen of the United States, and a resident of the city of Chicago, county of Cook, and State of Illinois, have invented certain new and useful Improvements in Suspenders, of which the following is a specification.

My invention relates to new and useful improvements in suspenders, and has for its object the provision in a suspender of means for imparting elasticity to the same.

Another object is the provision in a non-elastic suspender of resilient metallic means for imparting elasticity to the suspender.

Other objects will appear hereinafter.

The invention consists in the combinations and arrangements of parts hereinafter described and claimed.

The invention will be best understood by reference to the accompanying drawings forming a part of this specification, and in which,

Figure 1 is a front elevational view of a portion of a suspender, showing my invention applied,

Fig. 2 is a side elevational view of a vertical central section of my invention.

Fig. 3 is a fragmentary front elevational view of my invention, showing means of securing some of the parts in assembled relation, and

Fig. 4 is a fragmentary view of my invention, showing means of securing the resilient members in assembled position.

My invention is designed to be used with a pair of suspenders 4 which are constructed in the ordinary manner, so as to lie diagonally across the back of the wearer, having the lower end from which the diagonally extending members diverge secured together in the usual manner and provided with a sleeve which is adapted to receive and retain the wire loop 5. An elongated metallic strip 6 is provided, having a knuckle 7 formed at its upper end by curling the upper end thereof. The member 5 is inserted within the knuckle 7 so as to loosely and pivotally mount the member 6 upon the member 5. The member 6 is provided with an elongated slot 7 which terminates adjacent the upper end of the member 6. The opposite end of the slot 7 terminates at a greater distance from the other end 8 of the member 6 for a purpose which will be described herein. The end 8 of the member 6 is turned inwardly, as shown in Fig. 2.

The inwardly turned end 8 is provided with a tongue 9, which has laterally projecting ears. The tongue 9 is adapted to project through an elongated slot 11, which is formed in a metallic strip 10 constructed similar to the member 6. The slot 11 terminates adjacent the lower end of the member 10, so that the upper end of the slot 11 is at a greater distance from the upper end of the member 10 than is the lower end of the slot 11 from the lower end of the member 10. The lower end of the member 10 is curled to form a knuckle 12, in which is loosely positioned the loop 13, upon which is secured a clasp 14 which engages and retains in position the usual button engaging strap 15, which is used with suspenders. The upper end of the member 10 is provided with a tongue 16 which is inserted through the slot 7 and bent downwardly toward the main portion of the member 10 in a similar manner to the member 9. As is clearly seen in Fig. 1, the member 16 is also provided with ears which project laterally beyond the edges of the slot 7 in the same manner that the ears of member 9 project laterally beyond the edges of the slot 11. Similarly, the upper end of the member 10 is turned inwardly in a manner similar to the end 8 of the member 6. From the assembling of the parts by inserting the tongues 9 and 16 through the slots and bending the same downwardly upon the main portion of the body from which they project, it is apparent that the metallic strips 6 and 10 are locked in slidable position relatively to each other. It is also apparent that the members 6 and 10 are spaced apart, resulting from bending the ends inwardly as described. The distance separating the members 6 and 10 throughout their length will be the vertical distance of the ends of the inwardly turned portions from the plane of the main body of the members 6 and 10.

Punched inwardly in the same direction as the ends are turned in from each of the members 6 and 10, adjacent the inwardly turned end of each thereof and spaced apart so as to clear the slot in the cooperating member, are tongues 19 upon which are mounted loops 20 formed in wire spring members 21. The loop 20 is formed at each end of each of the members 21 and mounted in the manner shown in Fig. 1. When the 110 cooperating members 6 and 10 are secured together by means of the tongues 9 and 16,

as already described, the loops 20 are held upon the tongues 19 and prevented from slipping off the same, owing to the fact that there is not sufficient clearance between 5 the coöperating member and the end of the tongues 19. This is due to the fact that the tongues 19 extend inwardly from the members 6 and 10 approximately the same distance as the inwardly turned end portions of 10 the members. Formed intermediate the ends of each of the members 21 is a spiral coil 22, which is designed to impart resiliency to the members 21 so as to spring the ends apart when the same are forced 15 together.

In the operation of the device, upon a strain being exerted upon the member 14, the member 10 is moved downwardly, thereby bringing the ends of the members 21 20 into closer relation with each other. Upon the release of the strain from the member 14, the members 21, which are then under compression or strain, will tend to restore the member 10 to its former position. It is, 25 of course, apparent that the members 21 are always under a certain compression or strain in order to restore the slidably mounted coöperating members 10 and 6 to their normal position. Upon the member 14 being pulled 30 downwardly, the tongue 16 slides over the member 6 and the tongue 9 slides over the member 10. As this downward movement is continued, the lower edge 17 of the slot 7 engages within the tongue 16 and abuts 35 against the base thereof. Similarly, the edge 18 of the slot 11 passes under the tongue 9 and engages against the end thereof at its inner surface, thereby serving as a stop for the members 10 and 6 in their 40 slidable movement, and thus preventing such a strain being exerted upon the members 21, which would produce a permanent deformation thereof. It is thus seen that while I 45 use a fabric in the suspenders which is non-elastic, I nevertheless have a suspender which is elastic through the employment of my invention.

While I have illustrated and described the preferred form of construction for 50 carrying my invention into effect, this is capable of variation and modification, without departing from the spirit of the invention. I, therefore, do not wish to be limited to the precise details of the construction set 55 for h. but desire to avail myself of such variations and modifications as come within the scope of the appended claims.

Having described my invention, what I 60 claim as new and desire to secure by Letters Patent is:—

1. In a non-elastic suspender, a non-elastic member, having an elongated slot therein; a coöperating non-elastic member, having an elongated slot therein; a tongue

projecting from each of said members and 65 adapted to project through the slot in the coöperating member for securing said members in a slidably mounted position; and resilient means mounted upon said members for resisting the slidable, relative movement thereof, substantially as described. 70

2. In a non-elastic suspender, a non-elastic member, having an elongated slot therein; a coöperating non-elastic member, having an elongated slot therein; a tongue 75 projecting from each of said members and adapted to project through the slot in the coöperating member for securing said members in a slidably mounted position; resilient means upon said member for resisting the 80 slidable, relative movement thereof; and means on said members for securing said resilient means, substantially as described.

3. In a non-elastic suspender, a metallic member having an elongated slot therein; a coöperating member having an elongated slot therein; a tongue projecting from each of said members and adapted to engage in the slot formed in the coöperating member; and a wire spring member mounted upon 90 each of said members. 85

4. A device of the class described comprising a metallic strip, having an elongated slot therein; a coöperating member having an elongated slot therein; a tongue projecting from said metallic member and adapted to engage in the elongated slot in said coöperating member; a tongue projecting from said coöperating member and adapted to engage in said slot formed in said metallic member; other tongues projecting from said coöperating members adjacent the ends thereof; and resilient means mounted upon said last named tongues, substantially as described. 100 105

5. A device of the class described comprising a pair of non-elastic members secured together in slidable relation; resilient means for resisting the relative slidable movement of said members; and tongues on 110 said members for engaging said resilient means, substantially as described.

6. A device of the class described comprising a pair of non-elastic members secured together in slidable relation; resilient 115 means for resisting the relative slidable movement of said members; tongues on said members for engaging said resilient means; and means for limiting the slidable relative movement of said members, substantially as 120 described.

In testimony whereof I have signed my name to this specification in the presence of two subscribing witnesses.

ERNEST SEGEL.
